(57) **CLAIM**

The ornamental design for a lineman socket, as shown and described.

DESCRIPTION

FIG. 1 is a bottom perspective view of a lineman socket, showing a second embodiment of the design;

FIG. 2 is a top perspective view of the lineman socket of FIG. 1;

FIG. 3 is a right side elevation view of the lineman socket of FIG. 1;

FIG. 4 is a left side elevation view of the lineman socket of FIG. 1;

FIG. 5 is a front elevation view of the lineman socket of FIG. 1;

FIG. 6 is a rear elevation view of the lineman socket of FIG. 1;

FIG. 7 is a top view of the lineman socket of FIG. 1; and, FIG. 8 is a bottom view of the lineman socket of FIG. 1. The dashed lines depict portions of the lineman socket that form no part of the claim.
